UNITED STATES PATENT OFFICE.

GOTTLIEB W. FROELICH, OF ST. PAUL, MINNESOTA.

LAUNDRY-DRIER.

1,034,610.

Specification of Letters Patent. Patented Aug. 6, 1912.

Application filed June 3, 1910. Serial No. 584,877.

To all whom it may concern:

Be it known that I, GOTTLIEB W. FROELICH, of St. Paul, Ramsey county, Minnesota, have invented certain new and useful 5 Improvements in Laundry-Driers, of which the following is a specification.

The object of my invention is to provide a drier by means of which the heat will be more evenly and thoroughly distributed 10 among the racks and the clothes thereon.

A further object is to provide a drier which will be extremely economical to operate and of very simple, economical construction.

15 My invention consists generally in locating a baffle wall within the space inclosed by the drier, between which wall and the outer wall of the drier a flue is provided leading to the exhaust or exit.

20 In the accompanying drawings forming part of this specification, Figure 1 is a perspective view of a drier embodying my invention, Fig. 2 is a vertical, longitudinal, sectional view of the same, Fig. 3 is a detail 25 view illustrating the manner of supporting the drier rack.

In the drawing, 2 represents the front wall of the drier, 3 the side walls, 4 the rear wall and 5 the top, inclosing a chamber or 30 space 6.

7 represents a series of inverted T rails, the horizontal flanges of which form supports for the wheels 8 on hangers 9 to which the racks 10 are secured. These racks are 35 equipped with the usual rods 11 on which the garments to be dried are hung. The racks have the usual face plates 12 closing the upper portion of the front wall of the drier in the usual manner and the outer ends 40 of the rack supporting rails are provided with posts 12', of suitable construction. These rack supporting rails form substantial supports for the rack hangers and permit the racks to be moved easily back and forth 45 in the drier, even when filled with clothes. Any other suitable form of bar may be used in place of these T-bars, if preferred.

The lower portion of the wall 2 has a draft opening 13 and a door 14 therefor, 50 and in the lower portion of the chamber 6 I provide a radiator 15 supported on bars 16 and connected with a suitable source of heat, such as steam or hot water, preferably the former. In the rear of the racks 55 I provide an upright baffle wall 17 extending parallel with the rear wall 4 to a point

near the top 5, a throat or passage 18 being formed between said wall 17 and the top 5 leading to a diving flue 19 that is formed between the walls 17 and 4, and extending 60 transversely of the chamber 6, preferably from the top to the bottom thereof. The lower portion of the chamber 6 has a pipe connection 19', extending preferably out through the wall 3 and communicating with a waste or discharge pipe 20. The outer end 65 of the pipe 19' has a clean-out thimble 21 capable of removal to obtain access to the pipe 19', and supply and return pipes 22 and 23 are conducted through the wall 3 of 70 the drier to the radiator.

As indicated in Fig. 2, a circulation of air will be established through the opening 13 and up through the radiator and the racks and down the flue 19 to the exhaust pipe. 75 The baffle wall will separate the damp and heavy air from the fresh and heated air used in drying the clothes. Furthermore, a suction will be established in the diving flue 19 which will hasten the circulation of 80 air through the chamber 6 and cause the currents of air to flow faster through and among the garments hanging therein without drawing any of the fresh and heated air before it is laden with moisture. 85

By regulating the size of the opening 13 the degree of the draft through the chamber can be modified as desired.

I have shown a radiator coil located in the chamber 6, but do not confine myself to 90 this means of heating the chamber, as any other suitable apparatus may be used in place of it.

In driers as generally constructed, the 95 warm air, rising and passing between the clothes, becomes saturated with the moisture therefrom and drops back to the lower portion of the drier, to be again heated and lifted among the clothes. This operation continues, the moisture being dried out of 100 the air as it falls, but the soapy matter remaining in suspension and being deposited upon the clothes until, although the moisture may be removed from the garments, they will have a stiff, soapy feeling, which is 105 peculiarly incidental to the drying of clothes in an ordinary drier. With my diving flue construction this objection is avoided. The warm air rises among the clothes, gathers up the moisture therefrom and passing over the partition wall drops 110 down to the bottom of the flue 19 and passes

out through the exhaust pipe, while a fresh supply of air enters and is heated and discharged among the clothes. The partition prevents the descending currents of moisture laden air from flowing back among the coils of the radiator and rising again among the clothes. The result is that when the garments are dried they will be soft and flexible and that greasy, starchy feeling so often found in clothes dried in a laundry drier, will be entirely absent. The partition positively prevents the moisture laden air from returning to the heater and insures a rapid circulation of the air through the drier.

15 I claim as my invention:

1. A laundry drier comprising a casing having a heating chamber inclosed by said casing and a heating means therefor and an air inlet in its lower wall, a baffle wall provided within said casing and extending vertically therein from the floor of said casing to a point near the top thereof, said baffle wall being spaced from one of the upright walls of said casing to form a descending flue, the space between the upper portion of said baffle wall and the top of said casing forming an inlet opening to said flue, drying racks arranged within said chamber between said air inlet opening and the opening leading to said descending flue, said heating means operating to heat the air entering said inlet opening as it ascends within said chamber and before it reaches said

drying racks, said descending flue being closed at the bottom and provided in one of its side walls with an exit opening extending outwardly through said casing, substantially as described. 35

2. A laundry drier comprising a casing having a heating chamber and an air inlet 40 opening in its lower wall, drying racks in the upper portion of said chamber and heating means interposed between said drying racks and said air inlet opening, the currents of air from said inlet opening being 45 compelled to circulate around said heating means before reaching said racks, said heating chamber having a vertically arranged descending flue communicating with the upper portion of said chamber, the heated air 50 being compelled to pass through said racks before reaching the inlet opening to said descending flue, the lower walls of said descending flue having an exit opening and a pipe therefor leading outside said casing, a 55 circulation being established in said chamber upwardly through said racks and downwardly through said descending flue and through said exit opening to a point outside said chamber. 60

In witness whereof, I have hereunto set my hand this 29th day of October 1909.

GOTTLIEB W. FROELICH.
